WILLIAM H. GOLDRING, OF FRANKLIN, MASSACHUSETTS.

INKING MECHANISM.

1,108,433.

Specification of Letters Patent. Patented Aug. 25, 1914.

Application filed June 21, 1912. Serial No. 705,003.

To all whom it may concern:

Be it known that I, WILLIAM H. GOLDRING, a citizen of the United States, and resident of Franklin, in the county of Norfolk and State of Massachusetts, have invented certain new and useful Improvements in Inking Mechanism, of which the following is a specification.

This invention relates to inking mechanism, and its purpose is to provide means for improving the distribution of ink over the periphery of one or more inking rolls which transfer ink from an inking disk to the type.

In mechanism of the type of printing press for which the invention is especially designed, a plurality of inking rolls are caused to roll along tracks from an ink-distributing disk to the chase and to receive ink upon their peripheries from the distributing disk and deposit it upon the type while passing over the same. The distributing roll which is the basis of the present invention is mounted to travel with the inking rolls and to have rolling contact with the peripheries of said inking rolls, and is capable of endwise movement for distributing the ink evenly over the peripheries of the inking rolls. The invention also includes means for causing such endwise movement of the distributing roll in consequence of rotation imparted to it.

Of the accompanying drawings which illustrate one form in which the invention may be embodied: Figure 1 represents, in side elevation, portions of inking mechanism including an ink-distributing disk, a chase, a plurality of inking rolls for receiving ink from the distributing disk and depositing the same on the type, operating mechanism for said inking rolls, a track for said inking rolls, and means for distributing the ink upon said inking rolls in consequence of rotative movement of said rolls.

Fig. 2 represents a top plan view, partly in section, of the structure illustrated in Fig. 1. Fig. 3 represents a section, on a larger scale, of the mechanism for causing endwise movement of the distributing roll, the plane of the section being indicated by line 3-3 of Fig. 1. Fig. 4 represents a section, partly in elevation, the same being indicated by line 4-4 of Fig. 3. Fig. 5 represents an elevation of a bushing for supporting one end of a rod upon which the ink-distributing roll is mounted. Fig. 6 represents an

elevation of a washer which co-operates with the said bushing to clamp the latter in the desired position in the truck which carries the several rolls.

The same reference characters indicate the same parts wherever they occur.

A chase is indicated by dotted lines at 10, and a portion of an ink-distributing disk of the usual construction and arrangement is indicated by dotted lines at 11. The necessary quantity of ink is taken from the disk 11 and deposited upon the type in the chase by one or more inking rolls, four of such rolls being indicated at 12 in Fig. 1. These rolls in passing back and forth from the disk 11 to the chase 10 travel upon the tracks 13 in the well known manner. Each of the inking rolls has reduced ends or trunnions 14. These trunnions are mounted in the usual way in trucks 15. These trucks are connected by pivot pins 16 to rods 17 which are movable endwise in suitable bearings 18 and 18^a afforded by a pair of oscillatory arms or carriers 19. These arms are rigidly connected with each other by any suitable means such, for example, as the bar 20. The arms are mounted upon a rod or shaft 21 about which they are oscillated for the purpose of carrying the inking rolls back and forth from the distributing disk 11 to the chase 10. This movement of the arms 19 may be caused by any suitable mechanism which need not be shown or described since the same is well known. The rod or shaft 21 is mounted in stationary bearings such as those indicated at 24, which bearings are usually afforded by the frame of the printing press.

The inking rolls are held against the disk 11 or against the tracks 13 or against the type, as the case may be, by helical springs 22 which are coiled about the rods 17 and which are compressed between the bearings 18 and collars 23 on the ends of the rods 10 which are disposed in bearings 18^a.

All the mechanism thus far described is well known and is merely incidental to the present invention.

The ink-distributing roll or rolls herein-after described are mounted in the trucks 15 in such manner as to have rolling contact with the inking rolls 12. The distributing rolls receive their rotative movement from the inking rolls and utilize this rotative movement for the purpose of effecting longitudinal movement to distribute the ink

evenly over the peripheries of the inking rolls. Two ink-distributing rolls are indicated respectively at 25, 25. One of them is mounted in coöperative engagement with 5 one pair of rolls 12, while the other is similarly mounted in coöperative engagement with the other pair of rolls 12. The two distributing rolls 25 are the same in the matter of construction and arrangement, and 10 a description of one will be sufficient for both. Each roll 25 is mounted upon a rod 26. The ends of the rod are mounted in sockets 27 formed in bushings 28. One of these bushings is shown detached by Fig. 5, 15 but the arrangement of one end of the rod 26 in one of these bushings is shown in longitudinal section by Fig. 4. The bushings 28 are mounted in the trucks 15 in such manner as to be adjustable for the purpose 20 of adjusting the distributing roll with relation to the inking rolls. It is necessary to keep the periphery of the distributing roll against the peripheries of the inking rolls, and it is necessary to vary the adjustment of 25 the distributing roll from time to time because the inking rolls are, in practice, customarily covered with a composition of soft material which shrinks. For this purpose the trucks are provided with parallel surfaces 30 30 which in the present instance are afforded by ears 30. The bushings are provided with parallel surfaces 31 which are adapted to have sliding engagement with the surfaces 29. These surfaces permit the desired adjustability of the bushings to carry 35 the distributing roll toward and from the inking rolls and at the same time prevent rotation of the bushings. The bushings are further provided with lips or flanges 32 40 which are arranged against the inner sides of the ears 30, as shown by Fig. 4. The bushings are bored, as indicated at 33, for the reception of clamping bolts 34. The clamping bolts are inserted through washers 35 from the outer sides of the trucks and 45 through the bores 33 through which they extend loosely and into the ends of the rod 26 which are internally screw-threaded for coöperative engagement with the threads of 50 the bolts. The length of the bushings is slightly less than the thickness of the ears 30, and consequently when the bolts 34 are tightened the bushings are clamped tightly with relation to the trucks by coöperation of 55 the lips 32 and washers 35, the bushings and washers being drawn together by the bolts and by the rod 26 whose ends are seated in the bushings. The length of the distributing roll is considerably less than the distance 60 between the trucks 15, and the rolls are movably longitudinally with relation to the rods.

For the purpose of imparting longitudinal movement to the distributing rolls, coöperative screw-threads are provided which

cause such longitudinal movement in consequence of rotation of the distributing rolls. As shown by Fig. 3, one end of the distributing roll is provided with a bushing 36. This bushing is rigid with relation to the roll and is formed with an internal screw-thread 37. The complementary screw-thread for engaging that at 37 is indicated at 38 and is formed upon a sleeve 39 which is pinned or which may be otherwise affixed upon the rod 26. It is necessary to provide these screw-threaded elements at only one end of the roll 25, and the other end may have a smooth cylindric bearing upon the rod 26. It is desirable to restrict the length of the screw-threaded elements so that they may become unscrewed or detached from each other without moving the ends of the roll into engagement with other parts of the mechanism, because otherwise the roll might become bound against some other part of the mechanism in case it turned more freely in one direction than in the opposite direction. The length of the screw-threads 37 and 38 is restricted for this reason, and they are adapted to become detached from each other without causing the ends of the roll to engage the trucks 15 or bushings 28. Now, therefore, if the distributing roll should turn more freely in one direction 90 than in the opposite direction its internal screw-thread would in time become entirely unscrewed from the thread 38. I have provided means for causing the screw-threads to become operatively engaged after having 95 become disengaged, for the purpose of causing the distributing roll to move endwise in the desired manner after having become detached from the thread 38. Reinforcement of the screw-threads is caused by helical 100 springs indicated respectively at 40 and 41, the spring 40 being mounted upon the sleeve 39 at one end of the rod 26, and the spring 41 being mounted upon the opposite end of the rod. The springs act as follows:—When 105 the distributing roll moves endwise toward the spring 40 it engages the spring before the screw-threads become disengaged from each other, thereby compressing the spring. If the endwise movement is sufficient to 110 carry the screw-thread 37 beyond and out of engagement with the thread 38, endwise movement of the distributing roll will cease, notwithstanding continued rotative movement of the roll. Upon a reversal of rotative movement, the screw-threads will become automatically engaged with each other because of the force exerted upon the roll by the spring 40. The roll will thereupon 115 move endwise in the opposite direction toward the spring 41, and if its endwise movement in this direction should carry the screw-thread 37 beyond the thread 38 the spring 41 would be compressed, and upon 120 the next reversal of rotative movement the 125

spring would cause the screw-threads to again become operatively engaged therewith.

Although the invention is illustrated as employing two inking rolls 12 for each distributing roll 25, it is apparent that the distributing roll and the mechanism for causing its endwise movement are adapted to be embodied in substantially the same form if only one inking roll were employed. The relative positions of the inking roll and distributing roll might be varied to better advantage when only one inking roll is employed, but the operation of the distributing roll would be the same.

Having thus explained the nature of my said invention and described a way of constructing and using the same, although without attempting to set forth all the forms in which it may be made or all the modes of its use, what I claim is:

1. In a printing press, the combination with a chase, an inking roll therefor, and co-operative trucks for said roll; of a roll for distributing the ink upon said inking roll, means including clamping members for supporting said distributing roll, said trucks having slideways for said clamping members, whereby said distributing roll may be adjusted toward and from said inking roll, said clamping members having flanges bearing upon the inner sides of said trucks, and

means co-operating with the outer sides of said truck for pressing said flanges against the inner sides of the trucks to secure the 35 clamping members to the trucks.

2. In a printing press, the combination with a chase, an inking roll therefor, and co-operative trucks for said roll; of a roll for distributing the ink upon said inking roll, a 40 rod extending through and beyond the ends of said distributing roll, cap members engaging the end faces of said rod, said truck having slideways to receive said cap members, whereby said distributing roll is adjustable toward and from said inking roll, said cap members having flanges bearing upon the inner sides of said trucks, and screws extending toward each other through the outer ends of said cap members and into the ends of said rod, said rod being internally threaded for co-operating with said screws, said screws having heads at their outer ends for bearing against the outer sides of said trucks to clamp said flanges 50 relatively to said trucks, and to clamp said rod relatively to said cap members.

In testimony whereof I have affixed my signature, in presence of two witnesses.

WILLIAM H. GOLDING.
